UNITED STATES PATENT OFFICE.

CARL FRIEDRICH SIMON, OF STOLLBERG, GERMANY, ASSIGNOR TO CHEMISCHE FABRIK RHENANIA, OF AACHEN, GERMANY.

PUMP FOR RAISING LIQUIDS BY COMPRESSED AIR.

SPECIFICATION forming part of Letters Patent No. 723,743, dated March 24, 1903.

Application filed July 28, 1902. Serial No. 117,399. (No model.)

To all whom it may concern:

Be it known that I, CARL FRIEDRICH SIMON, a citizen of Germany, residing at Stollberg, Germany, have invented a certain new and useful Pump for Raising Liquids by Compressed Air, (for which I have made application for a patent in Germany, dated July 24, 1901,) of which the following is a specification.

The present invention relates to a pump in which the distributing-valve is a balanced piston moved, on the one hand, by a part of the air contained in the vessel for holding the liquid, which air is compressed by the liquid to be raised, and, on the other hand, by compressed air from the pipe or reservoir which supplies the air for raising the liquid.

In the accompanying drawings, Figure 1 is a longitudinal section of the distributing-valve mechanism. Fig. 2 is a transverse section on line A B of Fig. 1, and Fig. 3 is an elevation of the container with its liquid and compressed-air connections.

The liquid to be raised flows through pipe b, which has a check-valve c, into the empty container a. The air thus displaced escapes for the greater part up the pipe d and through the pipe e, which is above the valve f, the latter being open while the liquid is flowing into the container. A small part of the displaced air, however, is confined in the pipe g, which opens below the piston h, and is there compressed. The length of the part of the pipe g that extends into the container is so adjusted that at the moment when the container is full of liquid the pressure on the under side of the piston is sufficient to raise the latter, and thus to close the valve f, and hence the pipe d. At the same time this movement of the piston opens the pipe p, which supplies compressed air, and the latter flows by way of pipes i and d into the container, whereupon check-valve c is closed and the liquid is raised up pipe k. The said movement of the piston h puts into communication the compressed-air chamber and the vessel n, through the channel m, provided with a regulating-valve l. Compressed air at once passes into n and gradually produces a pressure therein which is regulated by valve o not to exceed a certain maximum—namely, a pressure insufficient to move the piston h against the pressure that is raising the liquid. When the level of the liquid in the container has fallen below the lower end of the pipe k,

the air in the container expands through this pipe, and the pressure in the vessel n is able to move the piston h back into the position in which the valve f is open, and the pipe p and the channel m are closed. As compressed air can no longer enter the container a, the air therein expands to atmospheric pressure, and the check-valve c opens to admit more liquid. The pressure in the vessel n also now falls to that of the atmosphere, with which it is in communication both through valve o and opening q, which is opened by the backward movement of the piston. The cycle of operations now repeats itself.

By means of the channel t, with its regulating-valve s, the pressure under the piston after the valve f is closed can be maintained at such a point as will prevent premature opening of the valve f and also the entrance into the cylinder of any portion of the liquid trapped in pipe g or vapors therefrom.

Having thus described the nature of this invention and the best means I know of carrying the same into practical effect, I claim—

1. In a pump for raising liquids by compressed air, a distributing-valve, means for directing a pressure of air entrapped and compressed by the liquid as it flows into the container against said valve to move it in one direction, and means adapted during the raising of the liquid from the container to direct a pressure of air from a compressed-air supply against the valve to move it in the opposite direction.

2. In a pump for raising liquids by compressed air, a distributing-valve, means for directing a pressure of air entrapped and compressed by the liquid as it flows into a container against said valve to move it in one direction, means adapted during the raising of the liquid from the container to direct a pressure of air from a compressed-air supply against the valve to move it in the opposite direction, and suitable connections between the compressed-air supply and the means for directing the entrapped air in the container against the valve.

In testimony whereof I have hereunto set my hand in presence of two subscribing witnesses.

CARL FRIEDRICH SIMON.
